Primary Examiner — Garth Rademaker(74) Attorney, Agent, or Firm — Buchanan Ingersoll & Rooney PC(57) CLAIM

The ornamental design for a stackable elevated planter, as shown and described.

DESCRIPTION

FIG. 1 is a front perspective view of a stackable elevated planter shown in an assembled condition;

FIG. 2 is a side view thereof;

FIG. 3 is an end view thereof;

FIG. 4 is a top view thereof;

FIG. 5 is a bottom view thereof;

FIG. 6 is a bottom view thereof, shown in a disassembled condition with the legs nested in the planter body;

FIG. 7 is a side view thereof; and,

FIG. 8 is an end view thereof.

Broken lines in FIGS. 1 through 3 depict an optional shelf and forms no part of the claimed design.

Broken lines in FIGS. 5 and 6 depict ribs on the bottom of the planter body and form no part of the claimed design.
